UNITED STATES PATENT OFFICE

FERDINAND PAVEL, JR., OF NEW YORK, N. Y.

DESIGN FOR A TOMATO JUICE COCKTAIL GLASS

Application filed November 24, 1931. Serial No. 41,843. Term of patent 3½ years.

To all whom it may concern:

Be it known that I, FERDINAND PAVEL, Jr., a citizen of Czechoslovakia, residing at New York in the county of New York and State of New York, have invented a new, original, and ornamental Design for Tomato Juice Cocktail Glasses, of which the following is a specification, reference being had to the accompanying drawings, forming part thereof.

Fig. 1 is a front elevational view of a tomato juice cocktail glass, looking in the direction of 1—1 of Fig. 4, showing my new design.

Fig. 2 is a side elevational view of the same, looking in the direction 2—2 of Fig. 4.

Fig. 3 is a rear view of the same, looking in the direction of 3—3 of Fig. 4.

Fig. 4 is a plan view of the same.

I claim:

The ornamental design for a tomato juice cocktail glass, as shown.

In testimony whereof I have affixed my signature this 23rd day of November 1931.

FERDINAND PAVEL, JR.
